UNITED STATES PATENT OFFICE.

ADOLF J. SCHNEIDER, OF BROOKLYN, NEW YORK.

SHOE.

1,294,179.

Specification of Letters Patent. Patented Feb. 11, 1919.

Application filed May 16, 1918. Serial No. 235,016.

To all whom it may concern:

Be it known that I, ADOLF J. SCHNEIDER, a citizen of the United States, residing at Brooklyn, in the county of Kings and State 5 of New York, have invented certain new and useful Improvements in Shoes; and I do hereby declare the following to be a full, clear, and exact description of the invention, such as will enable others skilled in the art 10 to which it appertains to make and use the same, reference being had to the accompanying drawings, and to characters of reference marked thereon, which form a part of this specification.

15 This invention relates, generally, to improvements in shoes; and, the present invention has reference, more particularly, to a novel shoe which is provided with the usual front opening connected with the upper of 20 the shoe, the closing portions of the upper being provided with the usual eyelets and fasteners for the shoe-lacing, but the quarters of the shoe being also provided with an opening and overlapping members for closing 25 said opening, means being at the same time provided for securing said overlapping members in their secured and closed relation about the back and ankle of the foot, and that the shoe can be quickly removed 30 from about the foot, without disturbing the front closed arrangement of the upper portions and of the lacing connected therewith.

The invention has for its principal object 35 to provide a shoe having the general appearance of a lace shoe into which the foot can be readily and quickly inserted, and can be easily and conveniently removed from the shoe without unfastening the lacing or disturbing the front closing portions or members 40 of the upper.

The invention has for its further object 45 to provide a shoe having an opening in the back comprising a pair of overlapping closing members, and a novel means for quickly bringing the overlapped members in their 50 securely closed relation, and adapting themselves about the foot with comfort to the wearer; and, at the same time providing a means which will not of itself, when walking, become separated or detached.

The invention has for its further object 55 to provide suitable means for the reinforcement of one of the said overlapping members, said means being of such construction that the overlapping members will readily

conform themselves to the general shape of the foot, and especially to the "hollow" at the side of the ankle, the closing means being also located upon one of the quarters of the shoe, at that point, whereby the parts 60 adapt themselves to the shape of the foot, so as to provide neatness and at the same time avoid all discomfort to the wearer.

A further object of the invention is to arrange the closing means in such a manner 65 that it is variously adjustable and that the shoe can be snugly fitted about the foot, irrespective of the size of the ankle of the wearer.

Other objects of the present invention not 70 at this time more particularly enumerated will be clearly understood from the following detailed description of the present invention.

With the various objects of the present 75 invention in view, the said invention consists, primarily, in the novel shoe herein-after set forth; and, the present invention consists, furthermore, in the novel arrangements and combinations of the various 80 devices and parts, as well as in the details of the construction of the said parts, all of which will be more fully described in the following specification, and then finally embodied in the clauses of the claim which are 85 appended to and which form an essential part of the said specification.

The invention is illustrated in the accompanying drawings, in which:—

Figure 1 illustrates in side elevation, a 90 shoe made according to and embodying the principles of the present invention, the overlapping members upon the back of the shoe, as well as the laced front upper-portions all being shown in their closed relations to the 95 main body of the shoe.

Fig. 2 is a rear view of the shoe, looking in the direction of the arrow α in said Fig. 1; and Fig. 3 is a similar view of the shoe, but showing the rear overlapping closing 100 members in their relation.

Fig. 4 is a detail longitudinal vertical section of the rear end or heel-portion of the shoe, said section being represented as being taken on line 4—4 in said Fig. 3.

Fig. 5 is a face view of fragmentary portions of the front closing members, and the lacing therefor, said view illustrating a novel arrangement of the uppermost eyelets, and an arrangement of the ends of the lac- 110

ing employed in connection therewith, in lieu of tying the ends of the lacing in the form of the usual bow-knot.

Figs. 6 and 7 are face views of the heel-portions of a shoe, showing modified arrangements of means for reinforcing the perforated rear closing and overlapping member with which the holding or retaining stud of the over closing and overlapping member is adapted to be brought into separable retaining engagement.

Fig. 8 is a front face view of one form of holding or retaining stud employed with the shoe; Fig. 9 is a rear face view of the said stud, in both of said views the various parts of the stud being shown in their assembled and secured positions upon opposite sides of the rear closing and overlapping member with which the stud is employed; and Fig. 10 is a transverse vertical section, said section being taken on line 10—10 in said Fig. 8.

Figs. 11 and 12 are face views of portions of the rear closing and overlapping member, with the said holding or retaining stud omitted from said views, said views showing the member provided with a series of holes or perforations, either of which is for adjustment of the said stud, two of such adjusted positions of the stud being indicated in dotted outline in said figures.

Fig. 13 is an edge view of a back-plate employed with the said holding or retaining stud; Fig. 14 is a transverse vertical section taken on line 14—14 in said Fig. 12; Fig. 15 is an edge view of a face-plate employed with the said stud; and Fig. 16 is a view of the fastening post employed with the said stud.

Fig. 17 is a face view, similar to Fig. 5, of fragmentary portions of the front closing members of the shoe and the lacing therefor, illustrating another novel and modified arrangement of the uppermost eyelets, and an arrangement of the ends of the lacing employed in connection therewith, showing another manner of securing the ends of the lacing, in lieu of tying the ends of the lacing in the form of the usual bow-knot.

Similar characters of reference are employed in the said above described views, to indicate corresponding parts.

Referring now to the said figures of the drawings, the reference-numeral 1 indicates a shoe of any desired form, style and construction, and the numeral 2 denotes the usual upper members which are provided at the front edges with an arrangement of eyelets, as 3, or other suitable lace-fasteners, for the reception of the usual lacing 4, for suitably closing the front end of the shoe over the usual tongue 5. As shown in Fig. 5 of the drawing, in addition to the usual arrangement of the eyelets at the upper end portions of the said upper members 2, auxiliary eyelets or perforations, as 6, may be

employed, or as shown in Fig. 17 of the drawings, a plurality of eyelets or perforations, as 7, may be disposed along the upper marginal edge-portions 8 of the said upper members 2. With these auxiliary eyelets or perforations the respective ends of the lacing may be used and arranged in the manner represented in either of said Figs. 5 or 17 to secure the upper members 2 in their closed relation, against separation, as will be clearly evident, without the necessity of tying the lacer-ends in the form of a bow-knot. The sole of the shoe is designated by the reference-character 9, said sole having the heel 10, and having secured thereto the vamp 11 which is formed with the usual heel-piece 12. Suitably inserted and secured between the heel and the inner insert or lining 13 of the shoe, is the end-portion 15 of an upwardly extending tab 14, preferably terminating at its free end-portion in a loop or pull-piece 16, as illustrated more particularly in Fig. 4 of the drawings. As shown in the various figures of the drawings, the rear portion or quarters 17 and 18 of the upper is also open, one of the said upper members or quarters, as 17, being formed with a rear closing overlapping member or flap, as 19, and the other upper member or quarter, as 18, being likewise formed with a rear closing overlapping member or flap, as 20.

The said overlapping members or flaps 19 and 20 are preferably of the marginal configurations indicated in Figs. 1 to 4 of the drawings; and, said members or flaps when brought into their overlapped relation, so as to close the rear or back end of the shoe, will assume the relative positions indicated more particularly in Fig. 2 of the drawings. As shown, the said overlapping member of flap 20 has suitably secured upon its outer face, and in the proper position, a reinforcing element 21 of leather or the like, said element 21 being usually of circular marginal configuration, and being made with an elongated hole or slot 22 in registration with a correspondingly disposed hole or slot 23 in the overlapping member or flap 20. Properly positioned upon the quarter 17 is a suitably constructed holding or retaining device, usually in the form of a stud adapted to be brought into engagement with perforated or slotted portions of the overlapping member or flap 20 and said reinforcing member 21.

The preferred form of holding or retaining device or stud is illustrated more particularly in Figs. 8, 9, 10, 13, 15 and 16 of the drawings, and the same consists, essentially, of a back-plate 24 of any desired marginal configuration, usually circular in form, said plate being depressed or dished, as at 25, and being also formed with a centrally disposed cone or funnel-shaped portion, as 26, provided with an opening 27. In this

cone or funnel-shaped portion 26 is rotatably disposed the cone-shaped head 29 of a screw 28, the screw-threaded portion or shank of which is passed through said opening 27 and 5 through any one of a series of holes or perforations 30 with which the quarter 17 is provided, see Figs. 11 and 12 of the drawings, and according to the adjustment desired.

10 The said back-plate 24 is disposed upon the inner face of the said quarter 17, and upon the outer face of said quarter 17 is a suitably formed face-plate 31 formed with a central opening 32. Resting against said 15 face-plate is the base 33 of a stud or post 34, said stud or post being provided upon its outer end with an enlargement or head, as 35, the said shank or post and its head or enlargement having an internally screw-threaded tubular portion, as 36, into which is screwed the screw-threaded shank of the said screw 26. Upon its under side or face, the said base 33 is made with a rearwardly projecting portion, as 37, which is snugly 20 fitted in the central opening 32 of the face-plate 31, and is also formed with a cone-shaped depression 38, so as to bring the various parts into a positively secured and binding relation, when assembled upon opposite sides of the said quarter 17, in the manner shown and as will be clearly evident 25 from an inspection of said Fig. 10 of the drawings. This construction of holding or retaining device or stud, with the novel arrangement of the two overlapping members or flaps 19 and 20, provides a ready and easily manipulated fastening and releasing means for the shoe, which may be quickly 30 opened at the back for the insertion or withdrawal of the foot, without disturbing the front closed and laced relation of the parts of the upper.

In lieu of the form of reinforcing member or element 21, tab-shaped or elongated reinforcing members 39 and 40, respectively provided with the stud-receiving holes or openings 41 and 42 may be employed, the said members or elements 39 and 40 being disposed upon the outer faces of the overlapping members or flaps 20 in the manner illustrated in said Figs. 6 and 7 of the drawings.

Furthermore, the arrangements and dispositions of the perforated or slotted portions of the flaps 20, and of the fastening device or stud upon the quarter 17, are such, that when the parts are brought into their closed and retaining relation, the closing or retaining device or stud will be located at a point opposite the "hollow" near the ankle 55 of the foot, so that in walking the parts will not become disconnected, nor cause any discomfort to the wearer of the shoe.

The construction, use and advantages of the invention will be readily understood 60 from the foregoing description of the pres-

ent invention and from an inspection of the drawings which accompany the same, and any further description of the invention is therefore deemed unnecessary. It will also be evident, that the invention is applicable 70 to all styles of shoes worn by men, as well as women, without detracting from the appearance of the shoe or rendering it uncomfortable to the wearer.

I am aware that some changes may be 75 made in the general arrangements and combinations of the various devices and parts, as well as in the details of the construction of the said parts, without departing from the scope of the present invention as set forth on 80 the foregoing specification, and as defined in the clauses of the claim which are appended to the said specification. Hence, I do not limit my present invention to the exact arrangements and combinations of the said devices and parts as described in the said specification, nor do I confine myself to the exact details of the construction of the said parts, as illustrated in the accompanying drawings.

I claim:—

1. A shoe having its quarters separated in the rear so as to provide an opening, closing flaps connected with and adapted to extend in overlapped relation from the marginal edge-portions of said quarters forming said opening, one of said quarters being provided with a holding stud, and one of said flaps having an opening adapted to be forced into retaining engagement with the said stud, said stud and the engaged portion of the flap 90 with said stud, when the shoe is worn, lying in the "hollow" at one side directly below the ankle of the foot.

2. A shoe having its quarters separated in the rear so as to provide an opening, closing flaps connected with and adapted to extend in overlapped relation from the marginal edge-portions of said quarters forming said opening, one of said quarters being provided with a holding stud, a reinforcing means 105 connected with one of said flaps, said reinforcing means and the flap having registering open portions adapted to be forced over the said stud into retaining engagement therewith, said stud and the engaged portions of the flap and reinforcing means, with said stud, when the shoe is worn, lying in the "hollow" at one side directly below the ankle of the foot.

3. A shoe having its quarters separated in 120 the rear so as to provide an opening, closing flaps connected with and adapted to extend in overlapped relation from the marginal edge-portions of said quarters forming said opening, one of said quarters being provided 125 with a series of stud-receiving perforations, a retaining stud detachably mounted in any one of said perforations for adjustment with relation to said quarter, and one of said flaps having an opening adapted to be forced into 130

- retaining engagement with the said stud, said stud and the engaged portion of the flap with said stud, when the shoe is worn, lying in the "hollow" at one side directly 5 below the ankle of the foot.
4. A shoe having its quarters separated in the rear so as to provide an opening, closing flaps connected with and adapted to extend in overlapped relation from the marginal edge-portions of said quarters forming said opening, one of said quarters being provided with a series of stud-receiving perforations, a retaining stud detachably mounted in any one of said perforations for adjustment with relation to said quarter, a reinforcing means connected with one of said flaps, said reinforcing means and the flap having registering open portions adapted to be forced over the said stud into retaining engagement therewith, said stud and the engaged portions of the flap and reinforcing means, with the stud, when the shoe is worn, lying in the "hollow" at one side directly below the ankle of the foot.
5. A shoe having its quarters separated in the rear so as to provide an opening, closing flaps connected with and adapted to extend in overlapped relation from the marginal edge-portions of said quarters forming said opening, one of said quarters being perforated, a retaining device comprising a back-plate having a centrally disposed funnel-shaped portion, a centrally opened face-plate, a post formed with a base having an annular flange disposed in the open portion of said face-plate, a head upon said post, the shank of said post being internally screw-threaded, combined with a screw having a cone-shaped head mounted in the funnel-shaped portion of said back-plate, the shank of said screw being detachably mounted in any one of said perforations for adjustment with relation to said quarter, said shank of the screw being also screwed into the internally screw-threaded part of the shank of said post, and one of said flaps having an opening adapted to be forced over said head into retaining engagement with the shank of said post, said stud and the engaged portion of the flap with said post, when the shoe is worn, lying in the "hollow" at one side directly below the ankle of the foot.
6. A shoe having its quarters separated in the rear so as to provide an opening, closing flaps connected with and adapted to extend in overlapping relation from the marginal edge-portions of said quarters forming said opening, one of said quarters being perforated, a retaining device comprising a back-plate having a centrally disposed funnel-shaped portion, a centrally opened face-plate, a post formed with a base having an annular flange disposed in the open portion of said face-plate, a head upon said post, the shank of said post being internally screw-threaded, combined with a screw having a cone-shaped head mounted in the funnel-shaped portion of said back-plate, the shank of said screw being detachably mounted in any one of said perforations for adjustment with relation to said quarter, said shank of the screw being also screwed into the internally screw-threaded part of the shank of said post, a reinforcing means connected with one of said flaps, said reinforcing means and the flap having registering open portions adapted to be forced over the said stud into retaining engagement therewith, said stud and the engaged portions of the flap and reinforcing means, with the stud, when the shoe is worn, lying in the "hollow" at one side directly below the ankle of the foot.
7. A shoe having its quarters separated in the rear so as to provide an opening, closing flaps connected with and adapted to extend in overlapped relation from the marginal edge-portions of said quarters forming said opening, one of said quarters being provided with a series of stud-receiving perforations, a retaining device comprising a back-plate having a centrally disposed funnel-shaped portion, a centrally opened face-plate, a post formed with a base having an annular flange disposed in the open portion of said face-plate, a head upon said post, the shank of said post being internally screw-threaded, combined with a screw having a cone-shaped head mounted in the funnel-shaped portion of said back-plate, the shank of said screw being detachably mounted in any one of said perforations for adjustment with relation to said quarter, said shank of the screw being also screwed into the internally screw-threaded part of the shank of said post, and one of said flaps having an opening adapted to be forced over said head into retaining engagement with the shank of said post, said stud and the engaged portion of the flap with said post, when the shoe is worn, lying in the "hollow" at one side directly below the ankle of the foot.
8. A shoe having its quarters separated in the rear so as to provide an opening, closing flaps connected with and adapted to extend in overlapped relation from the marginal edge-portions of said quarters forming said opening, one of said quarters being provided with a series of stud-receiving perforations, a retaining device comprising a back-plate having a centrally disposed funnel-shaped portion, a centrally opened face-plate, a post formed with a base having an annular flange disposed in the open portion of said face-plate, a head upon said post, the shank of said post being internally screw-threaded, combined with a screw having a cone-shaped head mounted in the funnel-shaped portion of said back-plate, the shank of said screw being detachably mounted in any one of said perforations for adjustment with relation to said quarter, said shank of the screw being also screwed into the internally screw-threaded part of the shank of said post, a reinforcing means connected with one of said flaps, said reinforcing means and the flap having registering open portions adapted to be forced over the said stud into retaining engagement therewith, said stud and the engaged portions of the flap and reinforcing means, with the stud, when the shoe is worn, lying in the "hollow" at one side directly below the ankle of the foot.

ing means and the flap having registering open portions adapted to be forced over said head into retaining engagement with the shank of said post, said stud and the engaged portions of the flap and reinforcing means with said stud, when the shoe is worn, lying in the "hollow" at one side directly below the ankle of the foot.

In testimony that I claim the invention set forth above I have hereunto set my hand 10 this 30th day of April, 1918.

ADOLF J. SCHNEIDER.
